UNITED STATES PATENT OFFICE

WILLIAM N. HUNTER, OF BLANCHESTER, OHIO

DEVICE FOR MAKING AND CARRYING CIGARETTES

Application filed December 3, 1931. Serial No. 578,786.

The object of my invention is primarily the provision of a useful, convenient and economical device which may be carried in the pocket, and which may be employed both in the making and in the carrying of cigarettes. Other objects of my invention relate to specific improvements in cigarette making devices, which improvements are not restricted in their utility to a device which is a combination maker and carrier for cigarettes.

It is thus an object of my invention to provide a cigarette making machine of the straight line type characterized by improved mechanism for compressing the tobacco and for tightening the belt.

These and other objects of my invention which will be set forth hereinafter or will be apparent to one skilled in the art upon reading these specifications, I accomplish by that certain construction and arrangement of parts, of which the following is a full, clear and exact description.

Briefly, in the practice of my invention, I provide a base member of hollow or tray-like form, which serves as a base for the cigarette making mechanism and a back for the cigarette case. This member has upturned sides for compressing the tobacco in the ends of the cigarette, and it likewise has guideways for a rolling device. I provide a rolling device which has a member forming a part of the cover of the cigarette case and a member forming a slide guided upon the base aforesaid. These two members are hinged together, which not only enables me more effectively to compress the tobacco in the initial stages of a rolling operation, but also enables me to conserve space. Finally, I provide a cover also having side flanges, which provide a pocket for carrying a supply of previously made cigarettes. The entire device is preferably made of sheet metal and finished as desired; or it may be covered with any suitable finishing material.

Reference is now made to the drawing, wherein:

Figure 1 is a plan view of my device in closed position.

Fig. 2 is a sectional view of the cover member thereof taken along the lines 2-2 in Fig. 5.

Fig. 3 is a sectional view taken along the lines 3-3 of Fig. 5.

Fig. 4 is a partial sectional view showing the relationship of parts in the initial stage of the rolling operation.

Fig. 5 is a complete sectional view of the device taken essentially along the lines 5-5 of Fig. 1, excepting that the cover is open. Figure 5 also illustrates the relationship of parts in the second stage of cigarette rolling.

Fig. 6 is a partial sectional view showing the third stage of cigarette rolling.

Fig. 7 is a partial sectional view showing the rolling operation as completed, and the manner in which the cigarette is ejected from the rolling device.

I have shown a base member 1 having upturned sides 6 extending substantially at right angles thereto. The upper edges of these sides are provided with guideways 7, which may take the form of turned over portions as shown, or may have other forms such as rolled or beaded configurations. The ends of the base member are likewise bent up as at 8 and 9, forming the entire base into a tray like structure. The metal forming the ends is conveniently longer than that forming the sides and is crimped over inside of the base so as to hold the ends of a belt as at 10 and 11. The belt 12 as shown is longer than the base itself, and consequently makes provision for a loop or fold thereof which is utilized in the cigarette forming operation. A member is provided to ride on the guideways, and consists of a piece of metal 13, wider than the base in part so that portions thereof extend beyond the sides of the base to form riders 14 and 15 engaging the guides 16.

7. The body of this member thus forms a bridge across the sides of the base; and in order to increase the strength of this bridge I may turn over a portion thereof as shown at 16. The rear part of the bridge is provided with interspaced curved members of piano hinge construction 17, designed to receive a pintle 18. Corresponding hinge projections are formed upon a top or cover member 19, whereby with the said pintle it may be hinged to member 13. This top member, which may be conveniently referred to as a roller member, is, through the agency of member 13, slidably mounted and guided upon the base. The rolling member may likewise have extended or downwardly curved portions 20 covering the guides and adapted to give a finished appearance to the case. At its forward end it bears turned over ears 21 and 22 so spaced that they will lie within the sides of the base. Between these ears is journaled a roller 23. The parts are so proportioned that there is a space between this roller and the forward edge of bridge portion when the roller member is closed as shown in Fig. 5. The magnitude of this space is preferably of the order of the width of a cigarette. The belt extends over the roller, but beneath the bridge member and the roller member. The roller member may, of course, be lifted on its hinge with respect to the bridge member. As a matter of convenience, in my device I prefer to add a metallic portion 19a overlying the member 19, so that between these two members there will be a space 24 thick enough to contain a package of cigarette papers when the roller member is in its lowermost position. Or I may construct the hinge so that there is a space between the member 19 and the member 13, depressing the forward end of 19 to the level of the portion 25. By either of these constructions the roller may be brought down into proper cigarette rolling position within the base member, and also means are provided whereby a projection on the closure member hereinafter to be described may overlie the portion 25, providing a neat and attractive closure.

The cover member has a top portion 27 provided with turned over sides 28 so spaced as to fit within the sides of the base member. The edges of these side members are turned over toward each other as at 29 and 30; and the end of my cover member is preferably rounded as at 30a so that in cooperation with the side members, there is formed a pocket into which finished cigarettes 31 may be slipped. The end of my cover member may be provided with a lip 32 to overlie and form a neat closure with the depressed portion 25 on the roller member.

In use, in the operation of rolling cigarettes, the roller member may be raised into the position shown in Fig. 4, and the belt 12 pushed down so as to form a pocket 12a be-

neath the roller. The tobacco 33 may then be placed in this pocket and spread out; and the roller member will then be swung down upon its hinge as shown in Fig. 5, whereby the tobacco is compressed into a compact cylinder in a pocket 12b behind the roller, there being sufficient clearance between the roller and the bridge member to permit this. The belt 12, excepting for that portion which lies beneath the bridge and roller members, will now extend flat along the inside of the base. The cigarette paper 34 is now placed flat upon the belt in front of the roller, usually after moistening the glued edge thereof, and the operation of making the cigarette is completed by grasping the roller member with the fingers and pushing the roller member forward to the other end of the base through such stages as are shown in Figs. 6 and 7. The roller member 19 slides on the base, since it is borne by the bridge member 13. It may be conveniently grasped by the turned over portions 20. This operation completes the making of the cigarette, which may then be ejected by pulling the roller member back slightly and/or swinging it upwardly on its hinge.

Since the sides of the base are interspaced the length of a cigarette, the cigarettes will be cleanly made without loose tobacco in the ends thereof; and when the finished cigarettes are placed in the carrier formed by the cover member, they will be slightly further compressed on the ends, whereby they are kept in excellent condition for smoking. The entire device folds into a compact case, in appearance not unlike the ordinary cigarette carrying case.

Having thus described my invention, what I claim as new and desire to secure by Letters Patent, is:—

1. In combination, in a device for cigarettes or the like, a base of tray form, a rolling mechanism mounted on said base and adapted to form a part of a closure therefor, and a cover member to complete the closure.
2. In combination, in a device for cigarettes or the like, a base of tray form, a rolling mechanism mounted on said base and adapted to form a part of a closure therefor, and a cover member to complete the closure, and means on said cover member to hold a supply of completed articles.
3. In a cigarette making and carrying device, a base of tray form, a cigarette rolling device slidably mounted on said base, said device having a portion to form part of a cover for said base, and a retainer for finished cigarettes pivoted on said base and of a length to complete the closure thereof.
4. In a cigarette making and carrying device, a base of tray form having upturned ends and sides, a belt attached to said ends and extending across said tray, guideways on said sides, a cigarette rolling device slidably

- mounted on said guideways and adapted to form part of a cover for said base, an additional cover member having portions adapted to extend within said base and retain 5 finished cigarettes, said cover being of a length to complete the closure of said base.

5. In a cigarette rolling device, a base of tray form having a back substantially in a single plane and upturned sides, guideways 10 on said sides and a rolling mechanism slidably mounted on said guideways, said mechanism comprising a bridge member and a member bearing a roller, said latter member being movable with respect to said bridge member 15 from a position in which said roller extends within said tray to a position in which said roller is above the side walls of said tray.

6. In a cigarette rolling device, a base of tray form having a back substantially in a single plane and upturned sides, guideways 20 on said sides and a rolling mechanism slidably mounted on said guideways, said mechanism comprising a bridge member and a member bearing a roller, said latter member being movable with respect to said bridge member 25 from a position in which said roller extends within said tray to a position in which said roller is above the side walls of said tray, said roller member being 30 pivoted to said bridge member, said members being so proportioned that a space is left between said roller and said bridge member of the order of the width of a cigarette.

7. In a cigarette rolling device, a base of tray form having a back substantially in a single plane and upturned sides, guideways 35 on said sides and a rolling mechanism slidably mounted on said guideways, said mechanism comprising a bridge member and a member bearing a roller, said latter member being movable with respect to said bridge member 40 from a position in which said roller extends within said tray to a position in which said roller is above the side walls of said tray, said roller member being pivoted to said bridge member, said members being so proportioned that a space is left between 45 said roller and said bridge member of the order of the width of a cigarette, said roller member having a raised portion on the body thereof adapted to form a holder for a package of cigarette papers.

8. In a cigarette rolling device, a base of tray form having a back substantially in a single plane and upturned sides, guideways 55 on said sides and a rolling mechanism slidably mounted on said guideways, said mechanism comprising a bridge member and a member bearing a roller, said latter member being movable with respect to said bridge member 60 from a position in which said roller extends within said tray to a position in which said roller is above the side walls of said tray, said roller member being pivoted 65 to said bridge member, said members being so proportioned that a space is left between said roller and said bridge member of the order of the width of a cigarette, said roller member having gripping projections extending beyond said sides of said tray.

9. In a cigarette rolling device, a base of tray form having a back substantially in a single plane and upturned sides, guideways 70 on said sides and a rolling mechanism slidably mounted on said guideways, said mechanism comprising a bridge member and a member bearing a roller, said latter member being movable with respect to said bridge member 75 from a position in which said roller extends within said tray to a position in which said roller is above the side walls of said tray, said roller member being pivoted to said bridge member, said members being so proportioned that a space is left between 80 said roller and said bridge member of the order of the width of a cigarette, said roller member having a raised portion in the body thereof adapted to form a holder for a package of cigarette papers, said roller member having gripping projections extending beyond said sides of said tray, said gripping members being bent over to form side closures 85 for said space for cigarette papers.

10. In a cigarette rolling and carrying machine, a base member of tray form having a back lying in substantially a single plane and upturned sides and ends, a belt extending between said ends, guideways on said 90 sides and cigarette rolling means slidably mounted on said guides, said means comprising a roller carrying portion adapted to form part of a cover for said tray, said portion being compressible until the top thereof does not extend substantially higher than the top edges of said sides, whereby the entire device when in closed position is not substantially thicker than the thickness of the cigarette.

11. In a cigarette rolling and carrying machine, a base member of tray form having a back lying in substantially a single plane and upturned sides and ends, a belt extending between said ends, guideways on said 95 sides and cigarette rolling means slidably mounted on said guides, said means comprising a roller carrying portion adapted to form part of a cover for said tray, said portion being compressible until the top thereof does not extend substantially higher than the top edges of said sides, whereby the entire device when in closed position is not substantially thicker than the thickness of the cigarette, and a cigarette carrying device adapted to complete the closure for said tray, and having carrier members depending within 100 said tray.

12. In a cigarette rolling and carrying device, a base of tray form having a back portion in substantially a single plane and upturned sides and ends, a belt extending loose- 105

ly between said ends, said ends being crimped over the ends of said belt, said sides bearing guideways, a bridge member slidably mounted on said guideways, a roller bearing member hinged to said bridge member and bearing a roller which is depressible into a position substantially wholly within said tray-like base, said roller bearing member adapted to form part of a closure for said base, a cigarette carrying means pivoted on said base at one end thereof and adapted to complete the closure thereof, said member having means extending wholly within said base when in closed position to carry a supply of complete cigarettes.
